UNITED STATES PATENT OFFICE

ARTHUR GAUL AND LE ROY GAUL, OF DIXON, ILLINOIS

DOOR ADJUSTER

Application filed June 19, 1931. Serial No. 545,560.

This invention relates to door adjusters or means for opening and closing doors and is especially adapted for garages and like buildings and has for the primary object, the provision of means connected to swinging doors and associated with an operating means, whereby a person standing at a distance from the doors may easily and quickly open or close both doors, simultaneously.

Another object of this invention is the provision of a door adjuster of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a front elevation illustrating a building having the entrance closed by swinging doors operating by means constructed in accordance with our invention.

Figure 2 is a similar view showing the doors in an opened position by the operation of the door adjuster.

Figure 3 is a sectional view illustrating the device with the doors in opened position.

Figure 4 is a similar view with the doors in closed position.

Figure 5 is a sectional view taken on the line 5-5 of Figure 2.

Figure 6 is a fragmentary perspective view illustrating an adjustable operating bar.

Referring in detail to the drawings, the numeral 1 indicates a building or garage, the entrance 2 thereof being closed by hinged doors 3. A bearing or support 4 is secured to the ceiling of the building 1 and slidably supports a rod 5 to which are pivoted links 6 that are in turn pivotally connected to the doors 3 as shown at 7 so that when one door is moved, the other door will be moved accordingly.

Extending from the building 1 is a supporting structure 8 carrying a channeled

guide 9 in which is slidably mounted a block 10 having a projecting portion 11 to which is pivotally connected an operating bar 12 that is in turn pivotally connected to one of the doors 3 as shown at 13. The operating bar 12 includes a pair of sections as shown in Figure 6 arranged in overlapping relation and adjustably connected by bolts or like fasteners 14 whereby the length of the operating bar may be varied as desired. An operating lever 15 is pivoted to the supporting structure and has one end pivotally connected to a link 16 that is in turn pivotally connected to the portion 11 of the block 10. The lever is pivoted intermediate its ends to the supporting structure and when swung in one direction on its pivot is adapted to cause the closing of the doors and when swung in the opposite direction is adapted to open the doors. The lever 15 as shown in the official drawings may be in the form of a half wheel and has secured thereto handles 17 whereby a person may obtain a firm grip thereon for the purpose of opening and closing the doors while standing at a spaced distance from said doors.

While we have shown and described the preferred embodiment of our invention, it will be understood that minor changes in construction, combination and arrangement of parts may be made without departing from the spirit and scope of our invention, as claimed.

Having thus described our invention, what we claim is:

1. In combination with a building having swinging doors, means for causing said doors to move in unison, a supporting structure extending from the building, a guide carried by the supporting structure, a block slidable in said guide, means connecting the block to one of the doors, and an operating means carried by the supporting structure and connected to the block for opening and closing the doors.

2. In combination with a building having swinging doors, means for causing said doors to move in unison, a supporting structure extending from the building, a block slidably mounted on the supporting struc-

ture, an adjustable rod pivotally connected to the block and to one of the doors, and an operating means connected to the block.

3. In combination with a building having swinging doors, means for causing said doors to move in unison, a supporting means extending from the building, a block slidably secured to said means, an adjustable bar between said block and one of the doors, a pivotally mounted lever carried by the supporting means, and a link pivotally connecting the block to said lever for opening and closing the doors by the movement of the lever.

In testimony whereof we affix our signatures.

ARTHUR GAUL.
LE ROY GAUL.
